CLAIM

The ornamental design for an combined album and support therefor, as shown and described.

DESCRIPTION

FIG. 1 is a front elevation view of a combined album
and support therefor showing my new design;

FIG. 2 is a left side elevation view thereof;

FIG. 3 is a bottom plan view thereof, the top view being substantially a mirror image of that shown;

FIG. 4 is a rear elevation view thereof;

FIG. 5 is a right side elevation view thereof;

FIG. 6 is a bottom plan view thereof in vertical position with the support flap in partially open condition;

FIG. 7 is a left end elevation view thereof, taken along line 7—7 in FIG. 6; and,

FIG. 8 is a perspective view thereof with the album and flap in fully open condition.
